ALFRED J. HAMLIN, OF VENICE, CALIFORNIA, ASSIGNOR TO ADDIE S. HAMLIN, OF LOS ANGELES, CALIFORNIA

CARBURETOR

Application filed August 20, 1928. Serial No. 300,637.

This invention relates to carburetors for gas engines.

One of the objects of the invention is to provide a carburetor which will enable a gas engine to attain a higher running speed.

Another object of the invention is to provide a carburetor by means of which smoother running of a gas engine in any gear and at any speed is effected.

Another object is to provide a carburetor which will enable a gas engine to "pick up" or start more quickly.

Another object is to provide a carburetor which will function in such manner as to prevent "killing" or "stalling" of the engine.

Another object is to provide a carburetor in which a variable idling jet is regulated by the engine choke. A further object is to provide a carburetor of the character stated by means of which higher efficiency and greater economy is attained.

Other objects and advantages will appear hereinafter.

The invention is illustrated in the annexed drawings which form a part of this specification and in which

Fig. 1 is a side elevation of the carburetor.

Fig. 2 is a side elevation of the carburetor taken from the side opposite to that shown in Fig. 1.

Fig. 3 is an end elevation of the carburetor.

Fig. 4 is a transverse vertical section of the carburetor taken on line 4—4 of Fig. 1.

Fig. 5 is a longitudinal vertical section of the carburetor taken on line 5—5 of Fig. 3.

Fig. 6 is a transverse vertical section of the idling jet and float chamber taken on line 6—6 of Fig. 1.

Fig. 7 is a longitudinal section of the float chamber taken on line 7—7 of Fig. 3.

Fig. 8 is a fragmentary side view of the carburetor and the choke connections to the main air intake valve operating arm and the idling jet operating arm.

Fig. 9 is a fragmentary transverse vertical section of the carburetor taken on line 9—9 of Fig. 5 showing the main air intake valve and the auxiliary air intake valve.

Fig. 10 is a horizontal section of the idling

jet taken on line 10—10 of Fig. 6 showing the jet valve operating arm.

Corresponding reference characters refer to the same parts throughout the several views.

My carburetor comprises generally a float chamber 1, an idling jet 2, a mixing chamber 3, a main air intake valve 4 and an auxiliary air intake valve 5 in the front end of said mixing chamber, a main gas jet 6 in said mixing chamber, a main jet regulating valve 7, a weighted mixture outlet valve 8 in said mixing chamber, a butterfly throttle valve 9 in the mixing chamber outlet 10, and a kick-out valve 11 controlling an opening 12 in the rear end of the mixing chamber.

The float chamber 1 is provided with an inlet 13 which connects with the gasoline supply (not shown).

The idling jet 2 of my carburetor is of special design and construction, comprising generally a pair of aligned jet tubes 14 and 15, a barrel 16 into which the ends of said tubes extend, and an idler jet valve 17 for regulating the admission of air into the jet. The tube 14 extends upwardly from a point near the bottom of the float chamber through the top of the chamber and through the lower end wall 18 of the barrel into a mixing chamber 19 in the lower end of the barrel. The lower end of the tube 15 extends downwardly through a threaded bore 20 in the upper end of the barrel 16 into the mixing chamber 19 and said tube has a thread 21 which engages the thread of said threaded bore, so that upon turning said barrel in one direction or the other, the tube 15 will be moved axially in the barrel, whereby the lower end of the tube will be adjusted closer to or further from the upper end of the tube 14 in the mixing chamber, as conditions require for varying the gas mixture.

A lock nut 22 screws on the upper tube thread 21 against the upper end of the barrel for locking the tube adjusted in the barrel. The bore of the tube 14 is restricted at its upper end at 23 and the bore of the tube 15 is restricted at its lower end at 24. The barrel 16 is provided with air inlets 25 leading into the mixing chamber 19. The valve 17 comprises a sleeve 26 turnably fitted on the

lower end of the barrel and provided with air inlet ports 27, which ports correspond in diameter at one end to the diameter of the barrel inlets 25, as indicated at 28, and taper from said end to points at their other ends, as indicated at 29, for varying the admission of air therethrough and through the inlets 25 into the mixing chamber 19. An operating arm 30 is adjustably clamped on the valve sleeve 26 by means of a clamp 31 formed on one end of the arm. The tube 15 leads into the carburetor outlet 10 above the closed position of the throttle valve 4 as indicated at 32.

In the mixing chamber 3 are a series of baffle plates—33, 34, 35, 36, 37 and 38—spaced progressively from the front end of the mixing chamber toward the rear end thereof, the rearmost plate 38 being spaced a short distance forwardly of the rear end wall of the chamber forming the rear portion of an outlet passage 39 between the plate and said wall. The baffle plates 33 to 38 inclusive extend entirely across the mixing chamber and upwardly from the bottom thereof to a horizontal wall 40 which is spaced below the top wall of the chamber and forms the remaining portion of the outlet passage 39, leading from the rear portion of the passage to the throttle outlet 10. A vertical partition 41 extends longitudinally of the mixing chamber midway thereof from the front end wall of the chamber to the first baffle plate 33 and from the bottom of the chamber to the top thereof, the upper portion of the rear edge 42 of said partition extending at an angle of substantially forty-five degrees (45°) upwardly from the first baffle plate 33 to the intersection of the front wall of the mixing chamber and the wall 40. The partition 40 divides the front end of the mixing chamber forwardly of the first baffle plate 33 into a main air and gas intake chamber 43 and an auxiliary air intake chamber 44, the main gas jet 6 being located in the chamber 43 and the valves 4 and 5 controlling air inlets 45 and 46 in the front wall of the mixing chamber leading into said chamber 43 and 44 respectively. The lower half of the baffle plate 33 is solid while the upper half thereof is perforated with openings 47. The upper half of the baffle plate 34 is solid while the lower half thereof is perforated with openings 48 slightly smaller than the openings 47 in the baffle plate 33. The lower half of the baffle plate 35 is solid while the upper half thereof is perforated with openings 49 slightly larger than the openings 48. The upper half of the baffle plate 36 is solid while the lower half thereof is perforated with openings 50 slightly larger than the openings 49. The lower half of the baffle plate 37 is solid while the upper half thereof is perforated with openings 51, slightly larger than the openings 50. The baffle plate 38 is solid and extends approximately only half the distance from the

upper wall 40 to the bottom of the mixing chamber 3, leaving an outlet 52 between the lower edge of the plate and the bottom of the mixing chamber, which outlet is normally closed by the weighted mixture valve 8, which is hinged at its lower edge at 53 in the lower rear corner of the mixing chamber 3 and carries a weight 54 which normally holds the valve closed with its upper end against a seat 55 on the lower edge of the baffle plate 38, but said valve is opened by the suction of the engine.

The main jet 6 comprises a tube formed with a vertical valve member 56, a horizontal member 57 extending from said vertical member intermediate its ends and a jet member 58 extending upwardly from the end of said horizontal member, said jet member being formed with a seat 59 in its upper end. The jet is mounted with its vertical member 56 in the float chamber 1 and its jet member 58 in the gas and air intake chamber 43, the member 56 extending from a point near the bottom of the float chamber to the top thereof, and the horizontal member 57 extending through the adjoining walls of the float chamber and the mixing chamber 3, with the jet 6 centrally disposed in the gas and air chamber 43 and immediately below the center of the choke tube 60 which is secured in the gas and air intake chamber. The valve member 56 is formed with a valve seat 56' immediately below the horizontal member 57 and a screw valve 61 is threaded in the valve member 56 to engage the seat 61 for regulating the flow of gasoline from the float chamber through the jet 6 and the choke tube 60 into the mixing chamber, the upper end of the screw valve extending through the top of the float chamber where it may be engaged by a screw driver for regulating the valve.

The jet regulating valve 7 comprises a stem 62, a valve head 63 on the lower end of the stem, a valve tube 64, heads 65 and 66 in the lower and upper ends respectively of the tube, a collar 67 on the stem, and a spring 68 surrounding the stem. The stem 62 extends through the tube 64 and the heads 65 and 66, while the upper end of the tube 64 is screw-seated at 69 in the upper wall of the mixing chamber and the base flange 70 of the throttle outlet casting in axial alignment with the jet member 58. The spring 68 is interposed between the lower head 65 of the tube and the collar 67 and normally holds the stem 62 and valve head 63 elevated with said head above the jet seat 59, so that gasoline may be introduced through the jet into the mixing chamber.

Means 71 are provided for closing the gas jet 6 when the throttle valve 9 is closed, which means comprises a lever 72 hinged at 73 to the throttle outlet casting, and an arm 74 secured on one end of the throttle valve shaft 75 and formed with a cam 76 for engaging

5 said lever. One end of the lever 72 is bent at 77 over the upper end of the jet valve stem 62 and a set screw 78 is threaded in said bent end for engaging the upper end of said stem when the lever 72 is swung down by the engagement thereof by the cam 76 when the throttle valve 9 is closed, whereby the jet valve stem 62 and valve head 63 are forced down, against the tension of the spring 68, 10 until the valve head 63 seats on the jet seat 59 and closes said jet. A set screw 79 is seated in the outer end of the arm 74 for engaging the throttle outlet flange 70 for limiting the closing of the throttle valve 9.

15 The main air intake valve 4 and the auxiliary air intake valve 5 are flat valves hinged at their lower ends respectively on shafts 80 and 81 journaled in the mixing chamber adjacent the front and lower walls of the mixing chamber, so that when said valves are swung forwardly they will close the air intake openings 45 and 46 and will open said openings when swung backwardly. An arm 82 is secured on the outer end of the valve shaft 25, to which arm is connected the choke rod 83. A stud 84 projects from one side edge of the main air intake valve 4 behind the auxiliary air intake valve 5 through an arcuate slot 85 in the partition 41 whereby the valve 5 is 30 closed when the valve 4 is closed, but the valve 4 may be opened without opening the valve 5.

Regulating means 86 is provided for regulating the resistance against which the auxiliary air valve 5 is opened, which means comprises a lever 87, a ratchet 88, a cam 89 formed on one end of said lever, and a flat spring 90. One end of the spring 90 is secured in a clamp 91 which is fitted on the outer end of the auxiliary valve shaft 81 and is adjustably secured on said shaft by a set screw 92. The other end of said spring engages the cam 89. The lever 87 is fulcrumed on one side of the mixing chamber 3 at 93. The ratchet 88 is articulate, being described from the fulcrum of the lever 87 and said ratchet is engaged by said lever to hold the lever in different positions, whereby the tension of the spring 90 through cam 89 is varied to vary the resistance at 45 which the auxiliary air valve 5 is opened by the suction of the engine.

The kick-out valve opening 12 is provided in the upper part of the rear end wall of the mixing chamber 3 and leads from the outlet passage 39. The kick-out valve 11 is a flat valve hinged at its lower edge at 94 to the outside of the rear end wall of the mixing chamber 3. Said valve is normally held closed by a spring 95 which is connected at one end to the upper part of the valve and at its other end to the base flange 70 of the throttle outlet casting.

An arm 96 is secured on one end of the 50 throttle valve shaft 75 to which arm is con-

nected the throttle lever connecting rod 97 for opening and closing the throttle valve.

An important feature of my invention is the connection of the idling jet valve operating arm 30, by any suitable means, such as a link 98, to the choke rod 83, whereby the idling jet valve 26 is closed when the choke is operated to close the main intake valve 4 to introduce a rich priming charge into the engine manifold through the idling jet and jet tube 15.

The operation of my carburetor is as follows: Assuming the throttle valve 9 to be closed and the main jet 6 closed by the jet valve 63, upon pulling out the choke, the main air valve 4 is swung open by the choke rod 83 and the valve 26 is turned also by the choke rod, through the link 98, so that said valve closes the jet ports 25, whereupon a rich mixture of gas is introduced into the engine cylinders from the float chamber 1 through the idling jet 2 and its tube 15 and through the carburetor outlet 10 above the closed throttle valve. Upon releasing the choke the main intake valve 4 and the idling jet valve 26 will open, the valve 4 uncovering the opening 45 and the inlet ports 27 of the valve 26 uncovering the jet inlets 25.

If the throttle valve is left closed, the main gas jet 6 will also remain closed, and no gas will be mixed in the mixing chamber 3 or pass therefrom, but air will be taken into the idling jet through valve inlet ports 29 and jet inlets 25 and the air mixed in the jet mixing chamber 19. The gas passing from the float chamber through the idling jet 2 and its tube 15 and through the carburetor outlet 10 into the engine cylinders will start and run the engine. By regulating the jet valve 26 by means of the choke, so that jet inlets 25 will be completely or partly opened, by the variable valve inlet ports 29, the mixture of gas fed into the engine and the speed of the engine will accordingly be varied. The running of the engine on the gas fed thereinto through the jet 2 is smooth at any speed in any gear in as much as a very fine mixture of gas is effected in the mixing chamber of the jet and a very fine adjustment of the jet is possible by means of the threaded engagement of the barrel 16 and tube 15.

If the throttle valve 9 is opened, when the choke is released and the engine started, the cam 76 will release lever 72, and the spring 68 of the main gas jet valve 7 will raise the jet valve head 63 off its seat 59 and open the jet, whereupon gasoline will be drawn by the suction of the engine from the float chamber through the jet into the air intake chamber 43, while air will be drawn through the main air intake opening 45 past the open main air intake valve 4, into said air intake chamber and the gasoline and air will mix and pass first through the choke tube 60; then through the perforations 47 in the baffle plate 33, into

the space between said baffle plate and baffle plate 34; then downwardly through said space and through the perforations 48 in baffle plate 34, into the space between baffle plates 34 and 35; then upwardly in said space and through the openings 49 in the plate 35, into the space between the baffle plates 35 and 36; then downwardly through said space and through the openings 50 in the baffle plate 36, into the space between the baffle plates 36 and 37; then upwardly in said space and through the openings 51 in baffle plate 37, into the space between the baffle plates 37 and 38; then downwardly in said space through the outlet 52, (the valve 8 being drawn open by the suction of the engine) and out through outlet passage 39 and the carburetor outlet 10 into the engine for driving the engine in the usual manner with the throttle open. As the engine speeds up the auxiliary air valve 5 is opened by the greater suction of the engine and an additional amount of air passes first through the auxiliary air intake chamber 44 and mixes with the gas behind the inclined rear edge of the partition and then passes through the openings 47 to 51 and between the baffle plates as above described and mixes with the gas drawn through the mixing chamber as above described. The gas in circulating between the baffle plates 33 and 34, 34 and 35, 35 and 36, 36 and 37, 37 and 38, and passing through the progressively smaller openings 47 to 51 inclusive in said baffle plates, is so thoroughly and finely mixed as to effect most perfect and complete combustion of the gas whereby a maximum power, speed, and smoothness in running the engine is attained, and a maximum smoothness of running of the engine at any speed in any gear.

In view of the fact that gas engines of varying compression and suction operate better with the gasoline at different levels in the float chamber 1, I have provided means for regulating the level of the gasoline in the float chamber to accommodate the requirements of the engine.

To the float 100 of the float chamber 1 is connected an arm 101 which is pivoted at 102 to the upper end of a screw 103 which extends through the lower wall of the float chamber in threaded engagement therewith. To the outer end of the arm 101 is pivoted a needle valve 104, which slides in the upper inner end of the inlet tube 13 of the chamber and is adapted to open and close ports 105 and to engage a seat 106 in said tube and shut off the inflow of gasoline when it reaches a predetermined level in the chamber as adjusted by the screw 103.

Having described my invention I claim:

1. In a carburetor, a mixing chamber provided with an air intake opening and an outlet, an air intake valve controlling said opening, a plurality of baffle plates spaced between

the front and rear end walls of the mixing chamber, said baffle plates, except that one near the rear end of the mixing chamber, being perforated, the perforations decreasing progressively in size in the plates as spaced from the front towards the rear of the mixing chamber, said mixing chamber being formed with an outlet passage leading from the space between the two rearmost baffle plates, to the carburetor outlet, and a fuel nozzle in the space between the front end wall of the mixing chamber and the first baffle plate.

2. In a carburetor, a mixing chamber provided with an air intake opening and an outlet, an air intake valve controlling said opening, a plurality of baffle plates spaced between the front and rear end walls of the mixing chamber, said baffle plates, except that one near the rear end of the mixing chamber, being perforated, the perforations decreasing progressively in size in the plates as spaced from the front towards the rear of the mixing chamber, said mixing chamber being formed with an outlet passage leading from the space between the two rearmost baffle plates, to the carburetor outlet, a mixture control valve in said passage normally closed but capable of being opened by the suction of the engine and a fuel nozzle in the space between the front end wall of the mixing chamber and the first baffle plate.

3. In a carburetor, a mixing chamber provided with a main air intake opening and an auxiliary air intake opening in the front end wall of said mixing chamber, a main air intake valve controlling said main air intake opening, an auxiliary intake valve controlling said auxiliary intake opening, a plurality of baffle plates spaced between the front and rear end walls of the mixing chamber, said baffle plates, except that one near the rear end of the mixing chamber, being perforated, the perforations decreasing progressively in size in the plates as spaced from the front towards the rear of the mixing chamber, a partition extending from the front wall of the mixing chamber to the first baffle plate and dividing the space into a main air intake chamber and an auxiliary air intake chamber into which said main air intake opening and said auxiliary air intake opening lead, said mixing chamber being formed with an outlet passage leading from the space between the two rearmost baffle plates to the carburetor outlet, and a fuel nozzle in the main air intake chamber.

4. In a carburetor, a mixing chamber provided with an air intake opening and an outlet, an air intake valve controlling said opening, a plurality of baffle plates spaced between the front and rear end walls of the mixing chamber, said baffle plates, except that one near the rear end of the mixing chamber, being perforated, the perforations decreasing

ing progressively in size in the plates as spaced from the front towards the rear of the mixing chamber, said mixing chamber being formed with an outlet passage leading from the space between the two rearmost baffle plates to the carburetor outlet, a mixture control valve in said passage normally closed but capable of being opened by the suction of the engine, and a fuel nozzle in the space between the front end wall of the mixing chamber and the first baffle plate, and a kick-out valve in said passage between said mixture valve and the carburetor outlet.

5. In a carburetor, a mixing chamber, a main air intake valve and a hinged auxiliary air valve, for controlling the admission of air into said mixing chamber, a throttle valve for controlling the outlet of mixture from said mixing chamber, and means for adjusting the resistance against opening of said auxiliary air intake valve, said resistance adjusting means comprising a lever, a cam on said lever, a flat spring connected to the pivot of said hinged auxiliary valve and engaging said cam, and a ratchet to be engaged by said lever to hold the same and said cam in different positions to adjust the tension of said spring.

6. In a carburetor, a float chamber, a mixing chamber provided with an outlet, an idling bypass including a bypass mixing chamber, a tube extending from said float chamber into said bypass mixing chamber, a second tube extending from said bypass mixing chamber to the carburetor outlet, means for adjusting the adjacent ends of said tubes closer together or further apart within said bypass mixing chamber, and means operated by the choke for admitting air into said bypass mixing chamber.

ALFRED J. HAMLIN.
